TWO SHELL WATER GAS SET

Joseph A. Perry, Swarthmore, and Edwin L. Hall,
Philadelphia, Pa., assignors to The United Gas
Improvement Company, Philadelphia, Pa., a
corporation of Pennsylvania

Application December 9, 1930, Serial No. 500,998

2 Claims. (Cl. 48—80)

The present invention relates to apparatus for the manufacture of carburetted water gas. The apparatus of the invention, while it may be otherwise used, is particularly adapted for the manufacture of carburetted water gas when heavy oil is used as the carburetting material. By heavy oil I mean to include those oils which deposit large quantities of carbon in the checkerbrick when vaporized in the ordinary carburetter. As an example of such oil mention may be made of so-called "Bunker C" oil.

In the use of such an oil a large quantity of heat is required for vaporization, but due to the characteristics of the oil, less heat is required for fixing the oil vapors than is the case with ordinary gas oil.

The best method of employing such oil is to vaporize it during the steam run on the top of the generator fuel bed by spraying it onto a zone which has been heated during the air blast step by secondary air which is applied marginally adjacent the top of the fuel bed and consumes producer gas generated by the primary air applied to the base of the fuel bed.

The vaporization of the oil on the top of the fuel bed, and the smaller quantity of heat required for fixing, makes it desirable to depart from the standard three shell carburetted water gas set.

According to the present invention a two shell set is provided which is cheaper to construct and is more compact than the ordinary carburetted water gas set without any sacrifice in efficiency of operation.

The invention will be described in connection with the attached drawings which form a part of this specification and which show forms of the apparatus chosen for illustration and in which,

Figure 1 shows one form of the apparatus in partial elevation and partial vertical cross section.

Figure 2 shows a modification of the apparatus of Figure 1 in partial elevation and partial vertical cross section.

Referring to Figure 1,

1 generally indicates the water gas generator which is provided with the fuel bed. The generator is further provided with the air blast supply means 3 and the steam supply means 4 for up air blasting and up steaming respectively. There is also provision for introducing secondary air marginally at the top of the fuel bed comprising the air supply means 5, bustle pipe 6 and

pipes 7. This secondary air produces the marginal hot zone indicated at 8.

The generator is further provided with the oil supply means 9 including the spray 10 which is adapted to spray oil on the hot zone 8. The generator is also provided with the gas offtake 11, leading to the superheater 12 and with the gas offtake 13 leading from the base of the fuel bed through the three-way valve 14 to the washbox 15. The superheater is also connected to the washbox 15 through the three-way valve 14 by connection 16. 17 is a steam supply means for downrunning. 18 is a gas offtake from the washbox to storage. 19 is the stack valve.

As shown the superheater is preferably constructed with the provision of the chamber arranged below the checkerbrick 21, and into which the connection 11 enters downwardly and tangentially. This chamber serves as a dust separator and is preferably provided as shown with a hopper bottom as 22 provided with the door 23 for the removal of accumulated dust and fuel particles.

Referring to Figure 2,

This figure shows a modification of the apparatus of Figure 1 in which there is provision of a separate dust collector instead of the dust collecting chamber in the base of the superheater.

The same numbers apply to identical parts except that in Figure 2, 20 is the separate dust collector into which the gas offtake 11 from the generator leads downwardly and tangentially and from which connection 11 leads off tangentially to the superheater 12. The dust collector is provided with the hopper 22 and the door 23 for the removal of dust and fuel particles.

In operation it will be obvious to those skilled in the art, that a wide variety of gas making cycles may be employed. One such cycle chosen for illustration will be described.

The generator fuel bed is blasted with air supplied at 3, the resultant combustion of the fuel storing heat in the fuel bed. The producer gas generated by this primary blast is burned in contact with fuel in the top of the fuel bed, by secondary air introduced marginally at 5, 6 and 7, producing the marginal hot zone 8 and storing heat therein. The resultant blast products pass through the gas offtake 11, through the dust collector (chamber 20 in superheater 12 in Figure 1 and the separate dust collector 20 in Figure 2). In the dust collector the fuel particles blown over from the generator fuel bed are de-

posited by centrifugal action to avoid clogging the checkerbrick.

From the dust collection the blast gases pass through the superheater checkerbrick storing their heat therein and thence to atmosphere through stack valve 19.

After sufficient heat has been stored by the blasting operation, the air blast is terminated, the stack valve shut, and an uprun is made with steam admitted through 4. As the resultant uprun water gas passes through and from the top of the fuel bed, it is carburetted by oil admitted through oil supply means 9 and oil spray 10, which sprays oil onto the previously heated marginal zone 8. The heat stored in this zone together with the heat of the uprun water gas, vaporizes the oil. The resultant oil vapors pass with the water gas, through offtake 11 and the dust collector and thence through the superheater checkerbrick where the oil vapors are fixed. The resultant carburetted water gas passes through offtake 16 and reversing valve 14 to the washbox 15 and thence through offtake 18 to storage.

After the uprun reversing valve 14 is reversed and a downrun is made with steam admitted through 17, the steam passes through the superheater checkerbrick, being superheated therein and thence by way of the dust collecting chamber and connection 11 to the top of the fuel bed and down through it, generating blue water gas which passes by way of connection 13 and reversing valve 14 to washbox 15 and thence to storage through offtake 18.

The superheated downrun steam passing through the top of the fuel bed assists in drying up, coking and consuming the residues of the oil sprayed on the marginal hot zone during the steam uprun. The remainder of the residues are consumed during the succeeding air blasting operation.

After the steam downrun a short steam uprun is made as a purge and the cycle repeated.

The applicant is aware of the fact that two shell sets have previously been proposed and employed in carburetted water gas manufacture. These two shell sets have not included the means for blasting the top of the fuel bed marginally with secondary air, and means for spraying oil onto this marginal hot zone. It is the inclusion of these means which permits the provision of a two shell set which is economical in construction, efficient in operation, and is particularly adapted

for the use of heavy oil as carburetted material.

It is desirable to provide dust collection means in this set, as the provision of the secondary air increases the quantity of gas passing through the top of the fuel bed. This results in an increase in gas velocity with an increased tendency to carry off particles of fuel.

It will be obvious to those skilled in the art that modifications may be made in the apparatus described without departing from the spirit of this invention.

We claim:

1. A centrifugally operating single shell, dust separating, dust collecting, and heat storing device for use in the manufacture of combustible gas, said device comprising in combination, a single shell, an empty dust collecting vessel having an open top in the lower portion of said shell, an inlet for dust laden gases entering said vessel tangentially and adjacent its upper portion, an outlet for dust adjacent the bottom portion of said vessel, a vessel containing refractory material mounted in said shell directly above said dust collecting vessel so that the open top of said dust collecting vessel forms an unobstructed conduit to said vessel containing refractory material, and means for letting off gas from the top of said vessel containing refractory material.

2. A two shell set for manufacturing carburetted water gas, said set including a generator adapted to contain an ignited fuel bed, air admission means and steam admission means and gas offtake means at the bottom of said generator, means for admitting secondary air adjacent the upper margin of the fuel bed in said generator, means for admitting oil directly onto the top of the fuel bed, an empty dust collecting vessel operating by centrifugal action, a gas conduit leading from the top of said generator and entering said dust collecting vessel tangentially, a vessel containing refractory material mounted on top of said dust collecting vessel and having unobstructed communication therewith, means for admitting steam to the top of said last mentioned vessel, and means for removing dust from said dust collecting vessel beneath said tangential inlet and beneath the connection between said dust collecting vessel and said vessel containing refractory material.

JOSEPH A. PERRY,
EDWIN L. HALL.
